BRAIDER CARRIER

Frank Mossberg, Attleboro, Mass., assignor to
Mossberg Pressed Steel Corporation, a corpora-
tion of Massachusetts

Application March 14, 1931, Serial No. 522,609

32 Claims. (Cl. 96—15)

This invention relates to a yarn package carrier for a braiding machine, and has for its object to provide a carrier which may operate on lighter weight yarn with lesser liability of rupturing or breaking the same than the average carrier in use.

Another object of this invention is the provision of a separate stop member and tension weight member so arranged that the stop member need not be lifted by the yarn, but yet is controlled by the tension weight member.

A further object of this invention is the provision of separate stop and tension weight members so arranged that the tension weight member will cooperate and assist the stop member in moving to a position to arrest the motion of the machine.

A still further object of this invention is the provision of mechanical connecting means between separate tension weight and stop members, permitting proper action of the tension weight and causing it to control the action of the stop member.

With these and other objects and advantageous features in view, the invention consists of a novel arrangement of parts more fully disclosed in the detailed description following, in conjunction with the accompanying drawings, and more particularly set forth in the appended claims.

30 In the drawings:

Fig. 1 is a side elevation of the braider carrier showing in dotted lines the yarn package mounted thereon and the path of the yarn from the package through the guides and beneath the tension weight guide in being drawn from the carrier;

Fig. 2 is a fragmental detail of the lower portion of the carrier showing the stop as moved to operative position;

Fig. 3 is an end view of the carrier with the top portion broken away;

Fig. 4 is a section on substantially line 4—4 of Figure 1;

Fig. 5 is a side elevation partly in section showing a modification;

Fig. 6 is an enlarged section of the latch spring in the base; and

Fig. 7 is a section on line 7—7 of Figure 6.

It is found in the operation of braider carriers of the type which have a vertically slidable tension weight member which operates the latch motion and which drop into a position to engage the lever for stopping the machine, that the weight of this tension member precludes its being used on small diameter yarn as the yarn must run beneath the weight and support it; and in order to

provide a construction in which the weight will not break the yarn, I have provided the stop and tension members separate and arranged a control mechanism between the stop member and tension weight member so that the tension weight when in operating tension position will hold the stop member in inoperative position, while the yarn is traveling beneath the tension weight, but which will cause the stop to move and drop into its operating position to stop the machine upon a breaking of the yarn, whereby a lighter tension weight may be used for the yarn and yet a heavy durable stop is provided for its operation in the machine; and the following is a detailed description of the present embodiment of this invention illustrating the preferred means by which these advantageous results may be accomplished:

With reference to the drawings, 10 designates the base of the yarn carrier having flanges 11 and 12 with a web 13 connecting the same for guiding and supporting the carrier in the sinuous path in the raceway plate of the braider machine, the same being driven by the usual gears engaging the stud 14. From the base 10 there extends the package spindle 15 upon which a suitable package 16 is mounted to be governed in its rotation by the latch member 17 pivoted at 18 at the base of spindle 15.

A pair of guide standards 19 and 20 extend upwardly from the base 10 and are positioned so that the spindle 15 is in line with them. A latch lift 21 is slideable upon the rod or standard 20 and is forced downwardly by means of a spring 22 encircling the rod 20. The latch lift has a finger 23 to engage beneath the lip 24 of the latch to raise the same in controlling the let-off action of the yarn.

A tension weight member 25 is formed of sheet metal by forming the same into generally U-shape having portions 26 and 27 provided with openings to receive the guide standard or rod 19 and slide therewith, and from the bridge portion 28 of this weight there extends an arm 29 having a finger 30 extending therefrom in generally the form of a hook beneath which the yarn extends. This weight is also provided with an arm 31 which engages the lip 32 on the latch lift 21 to raise the same, and also provides an abutment for purposes hereinafter mentioned.

A stop 33 slidably engages the rod 19 and is provided with a flange 34 which when in lowered position as illustrated in Figure 2, will engage the stop mechanism of the machine to arrest the motion thereof; and in order that this stop member may be lifted to inoperative posi-

tion, I have provided a support member 35 pivoted at 36 on the base, a finger 37 of which engages beneath the stop 33, while an arm 38 extends upwardly from the member 35, as shown in Figure 1, generally vertically and rests against the abutment surface of the arm 31 of the weight to prevent its swinging in a vertical plane about the pivot 36, whereby the stop member 33 is held in raised or inoperative position.

10 In operation, the yarn 39 extends from the package 16 through the pigtail guide 40 beneath the tension weight guide hook 30 outwardly through the pigtail guide 41 mounted on the top of rod 20 which extends above the rod 19, the weight being slidable along the rod 19 under action of the tension spring 42 to supply the sufficient amount of tension on the yarn, it being understood that as the tension weight is raised by the yarn to substantially the position illustrated in Figure 1, that it will raise the latch lift 21 and latch 17 to permit rotation of the package and thereby supply additional yarn for use, whereupon the weight will slide along its guide rods to take up this slack, the same being always in contact with the arm 38 to maintain it substantially in vertical position and thus cause the member 35 to support the stop 33. Should, however, the yarn break, the tension weight then will immediately slide along the rod 19 to a position illustrated in Figure 2, and its arm 31, will as illustrated in Figure 2, move from along the elongated surface of the arm 38 to the offset portion 43 thereof, permitting the member to swing in the vertical plane about the pivot, illustrated in Figure 2, and the weight to drop positioning its flange to engage the stop mechanism of the machine and thus arrest its motion.

In Figures 5, 6 and 7 I have illustrated in the base of the carrier an additional spring means 40 for the latch which may be used additionally to or in place of the spring 22. This means is provided by mounting a plunger 45 in a bore 46 in the base with a spring 47 forcing the same outwardly. The plunger is notched as at 48 to engage the edge of a notch 49 in the pin 18, whereby to rotate the pin 18 and in consequence the latch 17 which in this instance must be secured thereto to turn therewith.

It will be noted that the guide rod 20 extends 50 above the guide rod 19 and that the thread guides 40 and 41 are both carried on a single rod.

The pigtail guide 41 is removably secured at the top of the guide rod 20. A bracket 51 has a pair of spaced portions 52 and 53 engaging the rod 20 and rests on lugs 55 projecting therefrom. The portion 53 extends across to embrace the guide rod 19 and forms an abutment for the upper end of spring 42, the abutment being held in place by a spring 54 acting between it and the pigtail guide 41, whereby the spring 42 may be easily removed for replacement when desired.

By the foregoing arrangement, the part which must withstand the abuse of striking the stop mechanism and thus be necessarily of a somewhat heavy construction to withstand such shocks and jars, is not carried by the yarn, the yarn tension weight being separate therefrom and reciprocating independently thereof, whereby lighter thread may be used on the braider carrier without danger of breaking the same.

While I have described certain construction forms which embody the principles of my invention, it is obvious that other desired changes in arrangement may be made within the spirit

and the scope of the invention as defined in the appended claims.

I claim:

1. In a carrier for a braiding machine, a guide standard, a stop member slidably mounted on said standard, a separate tension weight for the yarn movably mounted on the carrier, and a member engaging said stop member for maintaining the same in inoperative position, and said separate member also engaging said weight to apply pressure at right angles to said standard, whereby the action of said member is controlled in its action by the movement of said weight. 80

15 2. In a carrier for a braiding machine, a stop member, means for movably mounting the same on the carrier, a separate tension weight for the yarn also movably mounted on the carrier, a pivoted member separate of said tension weight engaging and supporting said stop member and having a portion engaging said weight to apply pressure at right angles to its direction of movement to be controlled by the action of said weight. 90

20 3. In a carrier for a braiding machine, a stop member, means for movably mounting the same on the carrier, a separate pivoted member engaging and supporting said stop member and having an arm extending therefrom, and a tension weight independent of said pivot member movable in the path of movement of said arm to 100 obstruct the swinging of said member when in working position, whereby said stop member is held in inoperative position.

25 4. A carrier for a braiding machine comprising a base, a package spindle, a tension weight guide 110 standard, a tension weight on said standard, a stop member slidable on said standard, a support member pivotally mounted on said base and held in stop supporting position by said weight when said weight is held in working position by the 115 yarn, said weight being free to drop along its standard upon breaking of the thread, thereby permitting said support member to swing on its pivot and permit said stop member to drop to machine stopping position. 120

30 5. A carrier for a braiding machine comprising a base, a package spindle, a tension weight guide standard, a tension weight on said standard, a stop member slidable on said standard, a support member pivotally mounted on said base, an arm 125 on said member for engagement with said tension weight when the same is in operating position to hold said support in raised position, said weight permitting movement of said arm upon dropping, whereby said support is lowered 130 and the stop permitted to move to machine stopping position.

35 6. A carrier for a braiding machine comprising a base, a package spindle on said base, a tension weight guide standard, a tension weight thereon beneath a portion of which the yarn travels holding the same in elevated working position, a stop member slidably mounted on said standard, a support member pivoted to said base adjacent said spindle, and having a finger to engage said stop member, and an arm extending generally vertically along the package and engaging said tension weight to hold said stop in raised inoperative position, said tension weight being permitted to fall upon breaking of the yarn 140 to drop into contact with said stop member and permit said support member to move from beneath said stop, whereby it may drop into operative position to stop the machine. 145

7. In a carrier for a braiding machine, a guide 150

- standard, a stop member, a support member pivoted to swing in a vertical plane having a finger to hold said stop member in inoperative position, a tension weight mounted to slide on said guide standard, an arm on said support member engaging a portion of said weight to hold the stop member in inoperative position when the weight is raised and permit the stop member to move to operative position when the weight is lowered.
- 10 8. In a carrier for a braiding machine, a pair of support standards, a sheet metal tension weight having a pair of spaced guide portions slidably on one of said standards and a portion slidably engaging the other standard, an arm on said weight with a hook-shaped thread guide beneath which the thread extends, a separate stop member slidable on one of said standards, and means independent of said stop member and engaging said weight and blocked in its movement by some positions of the weight, whereby said weight controls the action of said stop.
9. In a braider carrier, a standard, a weight 25 slidable thereon, yielding means on said standard tending to force said weight in one direction, and abutment means mounted independently of the said standard for maintaining said yielding means in working position, said abutment means being removably mounted on said standard.
10. In a braider carrier, a standard, a weight 30 slidable thereon, yielding means on said standard tending to force said weight in one direction, and abutment means mounted independently of the said standard for maintaining said yielding means in working position, and yielding for removably mounting said abutment means in working position and removable against the action thereof.
11. In a braider carrier, a base, a pivot pin, a latch pivotally mounted therewith on said base, said pivot pin being secured to said latch to move therewith, and means acting on said pivot pin for moving said latch into engaging position.
12. In a braider carrier, a base, a latch movable in a vertical plane, a bore in said base, a plunger in said bore, a spring urging said plunger in one direction, and means for causing said plunger to move said latch to working position.
13. In a braider carrier, a base, a latch movable in a vertical plane, a pivot pin for said latch to move therewith, a bore in said base, a plunger in said bore, a spring urging said plunger in one direction, said pin and plunger having notches the side walls of which engage, whereby said latch is moved to working position.
14. A carrier for a braiding machine comprising a base, a package spindle on said base, a tension weight guide standard, a tension weight thereon beneath a portion of which the yarn travels holding the same in elevated working position, a stop member slidably mounted on said standard, a support member pivoted to said base adjacent said spindle, and having a finger to engage said stop member, and an arm extending generally vertically along the package and engaging said tension weight to hold said stop in raised inoperative position, said support member movable from beneath said stop upon breaking of the yarn, whereby it may drop into operative position to stop the machine.
15. In a carrier for braiding machines, the combination of a movable thread guide and tension element, a support for said element, a compression spring continuously acting on said element and tending to hold it in one position, and removable means mounted independently of
- said support serving as an abutment for one end of said spring.
16. In a carrier for braiding machines, the combination of a movable thread guide and tension element, a support for said element, a spring acting on said element and tending to hold it in one position, and a swinging member mounted independently of said support and in one position serving as abutment for one end of said spring.
17. In a carrier for braiding machines, the combination of a movable thread guide and tension element, a support for said element, a spring continuously acting on said element and tending to hold it in one position, a post adjacent said support, and removable means on said post serving as an abutment for one end of said spring.
18. In a carrier for braiding machines, the combination of a movable thread guide and tension element, a support for said element, a post adjacent said support, a spring on said support acting at one end on said element and tending to maintain it in one position, and a member mounted on said post and adapted to swing in a plane at an angle to the path of movement of said element, 100 said member in one position serving as an abutment for the other end of said spring.
19. In a carrier for braiding machines, the combination of a post, a thread guide and tension element movable lengthwise thereof, a second post adjacent the first, an element mounted on said second post and engageable with and movable by said thread guide, a spring on said second post continuously acting on said element and resisting movement thereof by said thread guide, 105 a spring on the first post continuously acting on the thread guide and tending to maintain it in one position, a member on said second post operable to serve as an abutment for one end of said spring, and a thread guide on said second post above said 110 member.
20. In a carrier for braiding machines, the combination of a base, a post projecting upwardly from the base and having its upper end free, a thread guiding and tensioning element mounted 115 on said post and movable thereon, a spring encircling said post and bearing at one end against said element, a second post adjacent the first, and a member on said second post normally serving as a abutment for the other end of said spring 120 and movable to permit removal of the spring.
21. In a carrier for braiding machines, the combination of a base, a post projecting upwardly from the base and having its upper end free, a thread guiding and tensioning element mounted 125 on said post and movable thereon, a spring encircling said post and bearing at one end against said element, a second post projecting upwardly from said base and lying adjacent the first, a fixed thread guide on said second post between 130 the ends thereof, a thread guide near the upper end of said second post, and a member mounted on said second post and having a portion serving as an abutment for the other end of said spring, said member being movable away from said first 135 post to permit free removal of said spring.
22. In a carrier for braiding machines, the combination of a base, a post projecting upwardly from the base and having its upper end free, a thread guiding and tensioning element mounted 140 on said post and movable thereon, a spring encircling said post and bearing at one end against said element, a second post projecting upwardly from said base and lying adjacent the first, a fixed thread guide on said second post between the ends 145

- thereof, a thread guide near the upper end of said second post, and a plate movably mounted on said second post, said plate having an opening in which the upper end of said first post is receivable and said plate adjacent said opening serving as an abutment for the other end of said spring. 80
23. In a carrier for braiding machines, the combination of a movable thread guide and tension element, a support for said element, a post adjacent said support, a spring on said support acting at one end on said element and tending to maintain it in one position, and a plate movably mounted on said post, said plate having an opening in which the upper end of said first post is receivable and having a portion adjacent said opening serving as an abutment for the other end of said spring. 85
24. In a carrier for braiding machines, the combination of a movable thread guide and tension element, a support for said element, a spring continuously acting on said element and tending to hold it in one position, and a removable member mounted independently of said support and in one position serving as an abutment for one end of said spring. 90
25. In a carrier for braiding machines, the combination of a movable thread guide and tension element, a support for said element, a spring continuously acting on said element and tending to hold it in one position, a post adjacent said support, and a removable member on said post serving in one position as an abutment for one end of said spring. 95
26. In a carrier for braiding machines, the combination of a movable thread guide and tension element, a support for said element, resilient means acting continuously on said element and tending to maintain it in one position, and removable means mounted independently of said support and acting on said resilient means to render it effective. 100
27. In a carrier for braiding machines, the combination of a movable thread guide and tension element, a support for said element, a spring encircling said support and continuously acting on said element to maintain it in one position, and removable means mounted independently of said support and acting as an abutment for one end of said spring. 110
28. In a carrier for braiding machines, the combination of a movable thread guide and tension element, a support for said element, a spring encircling said support and tending to maintain said element in one position, and a movable member mounted independently of said support and in one position acting as an abutment for one end of said spring. 120
29. In a carrier for braiding machines, the combination of a movable thread guide and tension element, a support for said element, a spring encircling said support and tending to maintain said element in one position, and a member mounted independently of said support and movable toward and away from said support, said member in one position thereof acting to render said spring effective. 125
30. In a carrier for braiding machines, the combination of a movable thread guide and tension element, a support for said element, a post adjacent said support, a spring on said support acting continuously on one end on said element and tending to maintain it in one position, and a removable member on said post serving as an abutment for the other end of said spring. 130
31. In a carrier for braiding machines, the combination of a movable thread guide and tension element, a support for said element, a post adjacent said support, a spring on said support acting at one end on said element and tending to maintain it in one position, and a member mounted on said post and normally extending beyond said support and serving as an abutment for the other end of said spring, said member being movable to release said spring. 135
32. In a carrier for a braiding machine, a pair of support standards, a sheet metal tension weight having a pair of spaced guide portions slideable on one of said standards, and a portion slidably engaging the other standard, an arm on said weight with a hook-shaped thread guide beneath which the thread extends, and means cooperating with said weight including a separate stop member slideable on one of said standards and assisted by said weight in arresting motion of the machine, said weight when in operating position being influenced by less than the full load of the stop. 140
